UNITED STATES PATENT OFFICE.

ALEXANDER J. LOGUIN, OF NORWOOD, OHIO, ASSIGNEE, BY MESNE ASSIGNMENTS, TO
ALLIS-CHALMERS MANUFACTURING COMPANY, A CORPORATION OF DELAWARE.

CONTROLLER.

1,087,170.

Specification of Letters Patent. Patented FEB. 17, 1914.

Application filed March 23, 1912. Serial No. 685,626.

To all whom it may concern:

Be it known that I, ALEXANDER J. LOGUIN, a subject of the Czar of Russia, residing at Norwood, in the county of Hamilton and State of Ohio, have invented certain new and useful Improvements in Controllers, of which the following is a full, clear, and exact specification.

This invention relates to controllers for

10. electric motors.

In the operation of controllers, especially in certain types of controllers, such as potential starters; reckless operators sometimes move the controller too rapidly through the 15 starting and running positions, over-running such positions. They then attempt to move the controller backward into the operative positions which they have overrun, thereby causing heavy arcing and burning.

20. This practice is not only damaging to such controllers but sometimes proves disastrous.

It is the object of my invention to partially take away from the operator the control of the motor controller at certain positions, making it absolutely necessary that the controller be positively stopped in such certain positions before a further movement of the controller can be made. This object is accomplished by providing the controller, 30 with a notched member for indicating positively the operative positions; and also with parts associated with the operating handle for coöperating with said notched member.

The various novel features of my invention will be apparent from the description and drawings and will be particularly set forth in the appended claims.

35. The invention is illustrated on the accompanying sheet of drawings in which—

40. Figure 1 is a front elevation of a controller equipped with my invention; Fig. 2 is a side fragmentary elevation, parts being in section, of the coöperating parts for positively stopping the controller in certain pre-determined positions; and, Fig. 3 is a sectional view taken along the line 3—3 of Fig. 2, disclosing details forming a part of my invention.

45. While I have illustrated my invention particularly in connection with potential starters, I do not limit my invention in this particular connection for it may be applied equally well to controllers of various types.

The normal operation of potential starters 50 is substantially in the same direction, a

movement through 180° forming a complete operation. The opposite halves of controller drums of such starters are therefore duplicates of each other. This means that in the ordinary potential starter there are 60 two off, two starting, and two running positions. As illustrated in Fig. 1, the controller 10 is in an off position. To mark the starting and running positions of the controller, the controller is provided with a 65 member or face plate 11 provided with notches 12 and 13 respectively. Mounted upon the controller shaft 14 is an operating handle 15 which is adapted to actuate the controller through its various positions, 70 The operating handle is provided with a latch 16, normally biased by a spring 17, to be forced into the notches 12 and 13 when the operating handle is rotated through the starting and running positions which are respectively marked by such notches. This latch 16 is adapted to be forced out of the notches 12 and 13 by a member 18 which is pivotally mounted at 19 in the handle 15 and which is adapted to be actuated to force said 80 latch out of said notches by a push button 20, normally held in the position shown in Fig. 2 by a spring 21 surrounding a reduced portion 22 of said push button. The spring-pressed latch 16 is pivotally mounted within 85 the member 18 on the pin 19. This latch 16 is also provided with projections or shoulders 23 adapted to be engaged by a coöperating portion 24 of the member 18. Without any further provision the operator could, by pressing and continuing to press the push button 20, move the controller from off through starting and running positions back to off position without stopping. Here 90 is where the danger arises. The operator, in carelessly operating the controller, may move beyond either a starting or running position and then desire to move back to either one of such positions. But in doing so, heavy arcing and burning will be caused. 95 This, as is well known, is to be avoided. To overcome these objections, I have provided cam members 25 and 26, which are adapted to take away part of the control of the controller from the operator by forcing the pivotally mounted member 18, against the pressure exerted on push button 20, and thus permit the spring 17 to force the pivotally mounted latch 16 into the notches which 100 mark the operative positions of the con- 110

troller. These cam members 25 and 26 are preferably secured to the face plate 11 of the controller and are respectively located directly in advance of the notches, so that by 5 the time the operating handle has reached an operative position the pivotally mounted spring-pressed latch 16 is absolutely free to engage said notches. It makes no difference how much pressure the operator may exert 0 on the push button, for when the operating handle is actuated for operating the controller, the control of said push button will be taken away from the operator. With this arrangement it is absolutely impossible 5 for the operator to run the controller through an operative position without the controller first being positively stopped at such operative position. After the controller has been stopped in such an operative 0 position by the latch 16 engaging one of the notches, the push button may then be pressed to force the member 18 against the shoulder portions 23 of the latch 16 to force said latch member 16, against the action of 5 spring 17, out of one of the notches to permit further movement of the controller handle.

There may be various modifications and arrangements of my invention other than 0 that which I have here shown and described, and it is my intention to cover all such modifications and arrangements which do not involve a departure from the spirit and scope of my invention as set forth in the ap- 5 pended claims.

What I claim as new is:

1. In a controller, the combination of a stationary member having a notch, a movable member having a latch adapted to engage said notch, another member adapted to hold said latch out of said notch, and a cam adapted to render said other member ineffective.

2. A controller comprising a movable part, 5 a stationary member having a notch, means adapted to engage said notch to prevent further movement of said movable part, another member adapted to hold said latch out of said notch, and a cam adapted to render 10 said other member ineffective and to positively stop said movable part in a certain position.

3. A controller comprising a movable part, a stationary member having a notch, 5 means adapted to engage said notch to prevent further movement of said movable part, another member adapted to be controlled by the operator to hold said latch out of said notch, and means associated with 10 said notched member to take away from the operator such control and to cause said movable part to be positively stopped in a certain position.

4. In a controller, the combination of a 5 member having a notch, an operating

handle, a latch pivotally mounted in said handle and being adapted to engage said notch, another member mounted in said handle and being adapted to hold said latch out of said notch; and a cam rendering said 70 other member effective.

5. In a controller, the combination of a member having a notch, an operating handle, a latch pivotally mounted in said operating handle and being adapted to engage said notch to prevent movement of the controller, means including a push button also mounted in said handle for holding said latch out of said notch, and means connected to said notched member for overcoming 80 the pressure on said push button to permit said latch to engage said notch.

6. In a controller, the combination of a member having a plurality of notches marking operative positions, an operating handle, means mounted on said operating handle and being adapted to engage said notches, means associated with the handle and being adapted to hold said means out of engagement with said notches, and means associated with said notched member and being adapted to render said last mentioned means ineffective before said controller is moved into said operative positions.

7. In a controller, the combination of a member having a plurality of notches marking operative positions, an operating handle, means mounted on said operating handle and being adapted to engage said notches, means associated with the handle and being adapted to hold said means out of engagement with said notches, and cams associated with said notched member and being adapted to render said last mentioned means ineffective before said controller is moved into 105 said operative position.

8. In a controller, the combination of a member having a notch marking an operative position, an operating handle, a latch pivotally mounted in said handle and being adapted to engage said notch to positively stop said controller, another member pivotally mounted in said handle and being adapted to hold said latch out of said notch, and a cam adapted to render said other member ineffective directly before the controller is moved into said operative position.

9. In a controller, the combination of a member having a plurality of notches marking operative positions, an operating handle, a spring-pressed latch pivotally mounted in said handle and being adapted to engage said notches to prevent further movement of said controller, a spring-pressed pivotally mounted member having a common pivot with said latch and being adapted to actuate said latch to hold it out of said notches, and cams mounted on said notched member ad- 125 jacent said notches to render said spring-pressed pivotally mounted member inef- 130

fective directly before the controller is moved into an operative position.

10. A controller for electric circuits comprising a stationary member having a notch, a latch adapted to engage said notch, a second member adapted to hold said latch out of said notch, and a cam for rendering said second member ineffective.

Milwaukee, Wis., Feb. 27, 1912.
In testimony whereof I affix my signature, in the presence of two witnesses.

Correction in Letters Patent No. 1,087,170.

It is hereby certified that in Letters Patent No. 1,087,170, granted February 17, 1914, upon the application of Alexander J. Loguin, of Norwood, Ohio, for an improvement in "Controllers," an error appears in the printed specification requiring correction as follows: Page 2, line 106, for the word "position" read *positions*; and that the said Letters Patent should be read with this correction therein that the same may conform to the record of the case in the Patent Office.

Signed and sealed this 24th day of March, A. D., 1914.
